ATTORNEY.

UNITED STATES PATENT OFFICE.

MARTIN CHRISTENSEN, OF ELMHURST, ILLINOIS, ASSIGNOR TO THE CHRISTENSEN MACHINE COMPANY, OF RACINE, WISCONSIN, A CORPORATION OF WISCONSIN.

BOOK-DELIVERY MECHANISM.

Application filed January 2, 1926. Serial No. 78,928.

This invention relates to book-stitching machines, and more particularly to the delivery mechanism for receiving the stitched or completed books.

In my prior United States Patent No. 1,423,647, of July 25, 1922, I have shown a delivery mechanism for signature-stitching machines which includes a plurality of endless belts. In practice it has been found that belt-type delivery mechanism necessitates considerable care and quite frequent replacement of the belts, due to wear, and the object of this invention is to provide a delivery mechanism in which the belts are eliminated and the books are moved along by a rack having a composite motion to produce the forward feed of the books.

The invention further consists in the several features hereinafter set forth and more particularly defined by claims at the conclusion hereof.

In the drawings, Fig. 1 is a side elevation view of delivery mechanism embodying the invention, parts being broken away and parts being shown in section along the line 1—1 of Fig. 3;

Fig. 2 is an end elevation view of the delivery mechanism;

Fig. 3 is a plan view of said mechanism, parts being broken away and parts being shown in section.

It will be understood that the delivery mechanism embodying the invention may be used in connection with any book-stitching machine, and the delivery end of one such machine is shown in my prior United States Patent No. 1,423,647, above mentioned, wherein mechanism including a fly is designed to remove the stitched signatures from the machine and deposit them on the delivery mechanism, preferably arranged at the front side of the machine.

The delivery mechanism forming the subject of this invention embodies a relatively fixed table or book-support and a movable table cooperating therewith.

The fixed table includes end frames 4 and spaced slats or bars 5 upon which the books are deposited.

The movable table includes a frame and spaced slats or bars 6 carried by this frame and movable within the spaces formed between the slats 5. The frame carrying the bars 6 includes transverse frame members 7

and longitudinally extending side frames 8 to which brackets 9 are secured adjacent each end. The brackets 9 at one end of this frame have vertically disposed slots 10 through which a shaft 11 passes and the brackets at the other end of this frame have similar slots through which a shaft 12 passes. Each of the shafts 11 and 12 are journaled in guide bars 13 slidably mounted in guideways 14 in the end frames 4. The bars 13 are connected by a transverse bar or bars 13'.

The shafts 11 and 12 are drivingly connected by a sprocket 15 on each shaft and a chain 16. The shaft 12 carries a sprocket-wheel 17 connected by a chain 18 to a sprocket 19 on a drive shaft 20. Since the bars 13 associated with the shaft 12 have to reciprocate, the chain 18 is provided with slack to accommodate this movement and a tensioning device takes up this slack, said device comprising an idler sprocket 21 mounted on a swinging arm 22 hinged at 23 to the fixed frame 4 and held by a spring 25 in engagement with the chain 18.

For reciprocating the bars 13, and hence the bars 6, a cam 26 on the shaft 12 engages a roller 27 on a shaft 28 carried by a bracket 29 on the fixed frame 4, the cam being held against said roller by springs 30 connected to loose collars 31 on the shaft 12 at one end and to the frame 4 at their other ends so that as the shaft 12 is rotated the cam 26 cooperates with said roller to produce the desired movement.

For moving the bars 6 up and down, there are cams 32 on the projecting ends of the rotating shafts 11 and 12 which engage rollers 33 on stud shafts 34 on the side frames 8.

The cam 26 and the cams 32 are so designed that the bars 6 are first moved upwardly from a position slightly below the level of the bars 5, as shown in full lines, to a position slightly above, as shown in dotted lines in Fig. 2, so that the books are raised off the bars 5. While in raised position the cam 26 acts to move the bars 6 through the associated frame members, including the bars 13, forward to carry the raised books away from the main machine and thereafter the cams 32 permit the bars 6 to be lowered to their full line position to deposit the books on the fixed table and then the cam 26

permits a return movement of the bars 6 below the fixed bars 5 to their initial position. Thus the books, deposited in overlapped relation by the fly previously mentioned, are intermittently raised by the movable table and advanced along the fixed table and carried away from the main machine.

I desire it to be understood that this invention is not to be limited to any specific form or arrangement of parts except in so far as such limitations are specified in the appended claims.

What I claim as my invention is:—

1. In a book-delivery mechanism, the combination of a fixed-table having spaced book-supports, a movable table having spaced book-supports working in the spaces between the book-supports of said fixed table, means for elevating, and depressing said movable table relative to said fixed table, and separate means for moving said movable table forwardly while elevated to advance the books along said fixed table.

2. In a book-delivery mechanism, the combination of a fixed table having spaced book-supports, a movable table having spaced book-supports working in the spaces between the book-supports of the fixed table and movable above the same, said movable table including a frame carrying its book-supports and slidable guide-bars, means for moving said frame vertically with respect to said guide-bars, and means for reciprocating said guide-bars while the frame is

elevated to advance the books along said fixed table.

3. In a book-delivery mechanism, the combination of a fixed table having spaced book-supports, a movable table having spaced book-supports working in the spaces between the book-supports of the fixed table and movable above the same, said movable table including a frame carrying its book-supports and slidable guide bars, rotating shafts journalled in said guide bars and provided with cams for moving said frame vertically, and means for reciprocating said guide bars while the frame is elevated to advance the books along said fixed table.

4. In a book-delivery mechanism, the combination of a fixed table having spaced book-supports, a movable table having spaced book-supports working in the spaces between the book supports of the fixed table and movable above the same, said movable table including a frame carrying its book-supports and slidable guide bars, rotating shafts journalled in said guide bars and provided with cams for moving said frame vertically, and means including a cam mounted on one of said shafts for reciprocating said guide bars while the frame is elevated to advance the books along said fixed table.

In testimony whereof, I affix my signature.

MARTIN CHRISTENSEN.
